UNITED STATES PATENT OFFICE.

EFISIO CADEDDU, OF VANCOUVER, BRITISH COLUMBIA, CANADA.

POTATO-SOWING MACHINE.

1,334,837.

Specification of Letters Patent. Patented Mar. 23, 1920.

Application filed June 18, 1918. Serial No. 240,578.

To all whom it may concern:

Be it known that I, EFISIO CADEDDU, a subject of the King of Italy, and a resident of the city of Vancouver, in the Province of British Columbia, Canada, have invented certain new and useful Improvements in Potato-Sowing Machines, of which the following is a specification.

My invention relates to improvements in machines for sowing potatoes, and the object of my invention is to devise a machine of this character which is capable of mechanically furrowing the ground, automatically depositing the seed potatoes in such furrows, and then filling in the furrows to cover the potatoes, such machine being self-propelling, thereby entirely eliminating the necessity of sowing potatoes by hand and enabling the work to be carried out more expeditiously and economically.

I attain this object by the construction illustrated in the accompanying drawings in which:

Fig. 1 is an end view of the machine.

Fig. 2 is a plan view.

Fig. 3 is a fragmentary detail view of the chute and slides.

Fig. 4 is a face view of the filling-in element.

Fig. 5 is a side view of the share and rack.

Similar figures of reference indicate similar parts throughout the several views.

1 indicates the frame of the machine formed of any suitable material, such as steel channels, the front and rear ends of the frame being supported on steerable wheels 2 and 3, while extending transversely across the frame intermediate its length is a rotatably mounted axle 4, the extremities of which are extended beyond the sides of the frame and provided with wheels 5 and 6. The steerable wheels 2 and 3 are resiliently mounted, the jaws carrying their respective axles being formed on their upper ends as flat plates 7 and 8 respectively, in which plates are secured at the four corners thereof bolts 9 carrying buffer springs 10 the upper ends of which bear against the under-side of plates 11 and 12, these plates being arranged under the heads of the bolts 9, the bolts themselves passing through these plates, which are respectively provided with vertical rods 13 and 14 passing rotatably through struts 15 and 16 rigidly secured on the upper side of the respective end channels of the frame. Arms 17 and 18 are secured

to or formed integrally with the plates 7 and 8, or they may be attached to any part of the steerable wheel arrangement, which arms are connected by suitable rods 19 and 20 to a hand lever 21, by the operation of which lever the wheels 2 and 3 may be inclined to change the direction of travel of the machine.

Extending laterally outwardly from one side of the frame are arms 22 and 23, in the ends of each of which adjacent their extremities are secured downwardly depending rods 24 and 25 respectively, carrying on their lower ends plates 26-27 and 28-29 respectively, these plates being arranged as shown in Fig. 2, that is, spreading outwardly from the rod to form, as it were, jaws having angularly inclined sides the apex of which jaws is rigidly secured to its respective rod, the mouths of the jaws facing each other. The upper edges of the plates 26-27 and 28-29 are turned over inwardly, as indicated at 30 in Fig. 4.

31 indicates a platform provided with bearings 32 and 33 in which are respectively mounted for vertical movement racks 34 and 35, to the lower ends of which racks are secured blades 36 and 37 similar to plow-share blades, the cutting points of which blades face each other, as shown in Fig. 2, and are in line longitudinally with the apex of each set of jaws formed by the plates 26-27 and 28-29. Meshing with the racks 34 and 35 are spur pinions 38 and 39 secured to rotatable shafts 40 and 41 provided with bevel pinions 42 and 43 meshing with bevel pinions 44 and 45 secured to vertical shafts 46 and 47 rotatably mounted on the platform 31, the upper ends of which shafts are provided with hand wheels 48 and 49, from which it will be seen that rotation of the handwheel 48 will raise or lower rack 34 and that rotation of handwheel 49 will raise or lower rack 35 and thus the blades 36 and 37 may be raised or lowered at will.

50 and 51 indicate hoppers for carrying the potatoes to be sown, which hoppers are arranged at a suitable height, being supported by supports 52 and provided with chutes 53 and 54, the length of which chutes is such that when a potato is discharged therefrom it will fall in the furrow made by the blade 36 or 37, as the case may be, as will be hereinafter described. As the potatoes must be sown at spaced intervals it is necessary to arrange for the intermittent dis-

charge of the same from the chutes, and this is effected by providing each chute with a pair of slides 55—56 and 57—58 respectively, the slides 55—56 being secured to opposite ends of an arm 59 fulcrumed in mid-length on a bracket 60 secured to the side of chute 53, while the slides 57—58 are secured to the opposite ends of an arm 61 fulcrumed in mid-length on a bracket 62 secured to chute 10 54, from which it will be seen that if the arms 59 and 61 are operated by a see-saw motion the upper slides will close the chutes while the lower slides will be withdrawn to open the part of the chutes below the upper 15 slides, or vice versa.

Rotatably mounted on suitable brackets at each end of the machine are shafts 63 and 64, the extremities of which at one end are extended adjacent the arms 59 and 61 respectively and on the end of each shaft are secured four fingers, indicated by the numeral 65, these fingers being arranged at right angles to each other and of such length that they will, as the shafts are rotated, engage 20 successively with the arms 59 and 61 below their fulcrum points and move the lower ends of the said arms toward their respective chutes, thus moving the lower slides inwardly to close the chutes and at the same 25 time moving the upper slides outwardly. As each finger passes clear the respective arms are returned to their normal position by means of springs 66, thus reversing the movement of the slides just described, from 30 which it will be seen that the see-saw motion hereinbefore mentioned is imparted to the arms 59 and 61 by their respective sets of fingers 65.

As only one chute is used at a time, it is 40 necessary to hold the arm of the chute which is temporarily out of use clear of the continuously rotating fingers which coöperate with that particular arm and this is effected by means of the levers 67 and 68, the end 45 of each of which, 69 in Fig. 3, is turned downwardly so that when the hand levers 70 and 71 connected to the levers 67 and 68 are moved longitudinally in the required direction the ends 69 will be moved to bear on 50 the lower end of the arms 59 and 61, as the case may be, to move such lower ends in toward their respective chutes and maintain them clear of their respective fingers 65, as shown in Fig. 3.

55 The finger shafts 63 and 64 are operated by shafts 72 and 73 mounted transversely of the frame at each end, being connected thereto by chain belts 74 and 75, and the shafts 72 and 73 are themselves operated by a line 60 shaft 76 and suitable gearing driven by a gasoline engine, suitable clutch gear, indicated by the numerals 77 and 78, being provided for the reversing of the direction of rotation of the shafts 72 and 73 so that the 65 machine may be moved in either direction at

will, the movement of the machine being effected by means of chain belts 79 and 80 extending between the shafts 63 and 64 and the axle 4 carrying the main wheels 5 and 6. Any suitable driving mechanism may be 70 used, however.

Having thus indicated the principal parts of my invention I will now describe its operation.

Assuming that it is intended to move the 75 machine in the direction of the arrow in Fig. 2, the hoppers 50 and 51 being filled with seed potatoes. The lever 67 is moved by means of hand lever 70 to carry the end 69 against the lower end of arm 59 and move 80 the lower slide inwardly to close the mouth of the chute 53, the hand lever being held against return movement by any suitable means, such as a quadrant 81 with which a dog 82 carried by the lever coöperates for 85 that purpose. The end 69 of lever 68 is moved to the extreme out position to allow freedom of movement of arm 61, and the rack 35 is dropped to bring the blade or share 37 into the earth-cutting position, the 90 rack 34 being raised to lift the blade 36 clear of the ground. On the engine being started, the machine travels in the direction of the arrow and the blade 37 cuts a furrow in the ground, into which furrow the potatoes are 95 discharged from the chute 54, the discharge being intermittent and regulated by the see-saw movements of the slides 57 and 58, the filling-in of the furrow after the potatoes are deposited therein being accomplished, as the 100 machine moves along, by the jaws formed by the plates 28 and 29. When the limit of travel in one direction is reached the machine is reversed by reversing the driving mechanism, the blade 37 having first of all 105 been raised clear of the ground and the blade 36 dropped into the earth-cutting position, and the lever 68 being moved to hold arm 61 against movement, with the arm 67 moved to permit movement of the arm 59. 110 Then the operation of the machine as it travels in the opposite direction is the same as described in the foregoing.

What I claim as my invention is:

1. In a motor propelled planter, a wheel supported frame, arms extending laterally from one side of the frame at each end thereof, transversely arranged furrow closing elements depending from said arms, a platform supported between the arms, reversely arranged furrow opening elements supported beneath the platform, and mechanism supported on the platform and connected with the furrow opening elements, whereby one or both of such elements may be rendered 120 operative or inoperative, as desired.

2. In a motor propelled planter, a wheel supported frame, arms extending laterally from one side of the frame at each end thereof, reversely arranged furrow closing ele- 130

ments depending from said arms, a platform supported between the arms, reversely arranged furrow opening elements supported beneath the platform, mechanism supported by the platform and connected with the furrow opening elements whereby one or both of such elements may be rendered operative or inoperative as desired, hoppers supported on the frame at each end thereof, feed chutes

leading from the hoppers and having the discharge ends thereof extended approximately to the furrow line, and means whereby either of said chutes may be rendered inoperative.

Dated at Vancouver, B. C., this 10th day 15 of June, 1918.

EFISIO CADEDDU.
